COMBINATION PRESSER FOOT AND GAUGE
FOR SEWING MACHINES

David Feigenbaum, Brooklyn, N. Y.

Application November 16, 1946, Serial No. 710,292

9 Claims. (Cl. 112—235)

1

This invention relates to a combination presser foot and gauge for sewing machines, hem, seam or like apparatus.

In practice it has been found desirable, in particular when using known cap machines, to reduce the number of sewing operations on the band material to be applied to the cap or hat body, to which band material lining and size strip are to be joined.

In order to reduce these sewing operations and manipulations of the work piece to a minimum, the present invention proposes certain improvements in presser foot structures. It is, therefore, one of the primary objects of this invention to provide means greatly facilitating adjustment, guidance and adaptability of the presser foot to the shape and dimensions (width) of the work piece which is to be stitched or sewn.

It is another object of the present invention to provide means affording simple construction and great efficiency in the handling and movements of the presser foot for the sewing operations.

Still another object of the present invention is to provide means ensuring substantially linear or parallel sliding movements of the gauge or like implement relatively to the presser foot proper and to provide further means for rapidly fixing said gauge in predetermined or desired position.

Yet, another object of the present invention is to provide means permitting pivotal movement of said gauge so as to employ the same also as an additional or auxiliary presser foot piece, which is kept under spring action.

Still a further object of this invention is to provide means ensuing straightening out and retaining the work piece in substantially flat condition without regard to its thickness or serving as a guide for one of the edges of said work piece.

With the above and other objects in view, the invention will be hereinafter more particularly described and the combination and arrangement of parts will be shown in the accompanying drawings and pointed out in the claims which form part of the specification.

Reference will now be had to the drawings wherein like numerals of reference designate corresponding parts throughout the several views, in which:

Fig. 1 shows in perspective a portion of a sewing machine equipped with a presser foot and gauge device made in accordance with this invention.

Fig. 2 is a top plan view of the presser foot and

2

gauge device made in accordance with this invention.

Fig. 3 is a bottom plan view of the device shown in Fig. 2.

Fig. 4 is an end view of the device of Fig. 2. Fig. 5 is a cross section taken along line 5—5 of Fig. 2.

Fig. 6 is a front elevational view of the device shown in Fig. 2.

Fig. 7 is a cross section taken along line 7—7 of Fig. 2.

Referring now more particularly to the drawings, Figs. 2 to 6 illustrate a combination presser foot and gauge device 10 made in accordance with this invention. The gauge device includes a pivotally supported guide lever or auxiliary presser foot 11 and an extension or slide member 12. Extension member 12 is arranged for sliding movement and extends on the upper surface 13 of the main presser foot 14. The main presser foot is provided with a slot 15 through which the needle 16 moves for the sewing operation and has further an open slot 17 extending from the upper surface 13 to the bottom surface 18 of the main presser foot portion. Slot 17 terminates in an end wall 17a. Lever 11 is adapted for movement within slot 17 and normally projects below the surface 18 of presser foot 14, as illustrated in dot-dash lines in Fig. 4. Lever 11 carries a pin 19 on which is removably and interchangeably disposed a spiral spring 20 which extends for abutment against an arm 21. This arm 21 is perforated at 22 to permit said pin 19 to project beyond arm 21. Lever or auxiliary presser foot member 11 is provided with the forward portion 11a with rounded end, with a reduced rearward portion 11b which terminates into a tongue-shaped portion 11c. Portion 11b terminates in end wall 11e for contact and cooperation with end wall 17a of slot 17. Portion 11c is adapted to rest on and engage the upper surface of extension member 12, as seen in Figs. 2 and 5.

It can thus be seen that forward portion 11a of lever 11 can either be swung upwardly about tongue-shaped portion 11c against the tension of spring 20 (which may be regulated in any known manner), or the forward portion 11a of lever 11 together with its portions 11b, 11c can be pressed upwardly (while end wall 11e engages slot end wall 17a) against the action of said spring 20 to a position in which the lower edge 11f is substantially in alignment with the straight bottom surface 18 of main presser foot portion 14 (Fig. 4).

In the present instance, presser foot 14 is pro-

55

vided with a projecting portion or nose 23 which is U-shaped in cross-section and forms a lateral guide for the extension member 12, which is further guided by its engagement with a set screw 25 along slot 24.

Presser foot 14 has further an upwardly projecting guide portion 26 which is bent at 28 and carries a screw bolt 27 for attaching arm 21 to portion 26. Portion 26 of the presser foot extends above the latter and is so curved at 28 as to form an additional lateral guide for the forward edge or end 29 of extension member 12. Extension member 12 is further provided with a downwardly extending abutment flange or rim 30 which in retracted position of member 12 comes to lie flush with the bottom surface 18 of presser foot 14 (indicated in dot-and-dash lines).

In order to slide extension member 12 relatively to presser foot 14, all that is to be done is to loosen set screw 25 and then to slide member 12 along guides 23 and 26 so that rim 30 extends beyond the lateral end 31 of presser foot 14. Rim 30 of member 12 is thus guided parallel to edge 31, while the walls of slot 24 engage the stem 25a of set screw 25. Projecting portion 32 of slide member 12 will move underneath the lower surface of tongue-shaped portion 11c of lever 11 without interfering with the position of the spring supported lever 11.

Presser foot 14 is further provided with an upwardly extending portion 33 equipped with a slot 34 for the engagement of a screw 35 provided on foot bar 36 of the sewing machine 37 (Fig. 1), whereby the presser foot and gauge device can be readily joined to the foot bar 36 of a sewing machine.

As seen in Fig. 1, work piece 40 is positioned on the sewing machine as usual on work plate or platform 41 for sewing or stitching operations. The work piece 40 may first be guided below the bottom surface 18 of the main presser foot 14 and also with its free edge 42 lengthwise of guide edge 11d of the auxiliary member or lever 11. A seam 43 is obtained in the course of the sewing operation during which the flat base surface 18 of the presser foot 14 retains the folded over portion 44 of the work piece 40 in position, while needle 16 carrying the thread (not shown) moves through the closed presser foot slot 15.

If it is desired during further sewing operations, as it is often the case in cap machines, to attach or stitch size band and lining cover to the material of the hat body, work piece 40 may be guided along an auxiliary guide bar 45 of a well-known auxiliary gauge (indicated in dotted lines). Upon adjustment of auxiliary gauge 46 by means of slot 47 and set screw 48, as may be easily realized, slide extension member 12 with its upwardly curved forward part 12a may be spaced from the lateral edge 31 of presser foot 14 and its curved forward part 14a and moved to a position in which flange 30 enlarges the bottom surface 18 of the presser foot and abuts against bar 45, thereby effectuating and aiding in the retention of the projecting work piece portion on platform 41 which work piece is guided along bar 45.

In such sewing operation, auxiliary presser foot member 11 will recede to a position as shown in full lines in Fig. 4, in which said member permits transport of the work piece on the platform while said member 11 rides with relatively slight pressure on the work piece 40.

It follows from the above disclosure, that according to this invention, there has been achieved a presser foot structure provided with a connection for the foot bar of a sewing machine, which structure consists of a main foot member with a substantially flat bottom surface, which has a lateral edge and also a slot directed substantially parallel to said lateral edge. The presser foot structure is further equipped with an auxiliary member accommodated for movement in the aforesaid slot and provided with a guide edge adapted to extend beyond said bottom surface of the main foot member; a spring element is arranged to engage one end of said auxiliary member for maintaining the latter in downwardly projecting position. Further attached to the presser foot structure is an extension member located on top of said main member and slidably thereon, said extension member including a flange adapted in one extreme position of said slidable extension member to lie adjacent said lateral edge and substantially flush with the bottom surface of said main member. This flange is spaced in another extreme position of said slidable extension member from said lateral edge and enlarges the bottom surface of said main member. The auxiliary member includes also a tongue-shaped end piece which lies on the top of said main member whereby said auxiliary member may be moved against the action of said spring element about said tongue-shaped end piece within said slot so as to cause said auxiliary member to assume a receding position in which said guide edge will be located substantially flush with said bottom surface of said main member to thereby obtain a substantially uninterrupted flat bottom surface.

It is further to be observed that the spring 20 may be easily adjusted as to its tension by any known means or may be readily replaced by another spring exerting an appropriate pressure on said auxiliary presser foot for application to the fabric or material to be worked upon.

In accordance with the above, it is well understood that deviations and changes may be made from the embodiment herein set forth without departing from the spirit of this invention.

Having thus described the invention, what is claimed as new and desired to be secured by Letters Patent is:

1. A presser foot structure of the character described comprising a main foot portion having a substantially flat bottom surface terminating into a lateral edge, an upwardly curved portion forming the forward end of said main portion, said main portion and said curved portion being provided with a slot directed substantially parallel to said lateral edge and defined by an end wall, an auxiliary member accommodated for movement in said slot, said auxiliary member including a guide edge and being normally held in a position projecting beyond said curved portion and said bottom surface, spring means engaging said auxiliary member to maintain the latter in said projecting position whereby the lateral end of a work piece may abut against said guide edge of said auxiliary member, oppositely arranged guide pieces disposed at said curved portion and at said main portion, an extension member positioned on top of said main portion and slidably engaging said opposite guide pieces, said extension member including a flange adapted in normal position of said extension member for location adjacent said lateral edge and substantially flush with the bottom surface

of said main portion, said flange in extended position of said extension member being spaced from said lateral edge and aiding in the detention of the work piece when placed beneath said main foot portion and projecting beyond said 5 guide edge, a tongue-shaped end piece forming part of said auxiliary member and terminating in an abutment for engagement with said end wall of said slot, said tongue-shaped end piece being seated on said main portion whereby said auxiliary member may be moved against the action of said spring means about said tongue-shaped end piece within said slot so as to cause said guide edge of said auxiliary member to recede to a position substantially flush with said 10 flat bottom surface of said main portion to further aid in the detention of said work piece when projecting beyond said guide edge, and means upwardly extending from said main portion for connection with the foot bar of a sewing machine.

2. A presser foot structure of the character described comprising a main foot member having a substantially flat bottom surface terminating into a lateral edge, said main member being provided with a slot directed substantially parallel to said lateral edge, an auxiliary member accommodated for movement in said slot, said auxiliary member including a guide edge adapted in projecting position to extend beyond said bottom surface, spring means engaging one end of said auxiliary member to maintain the latter in said projecting position, an extension member located on top of said main member and slidable thereon, said extension member including a flange adapted in one position of said slidable extension member to lie adjacent said lateral edge and substantially flush with the bottom surface of said main member, said flange in another position of said slidable extension member being spaced from said lateral edge and enlarging the bottom surface of said main member, a tongue-shaped end piece positioned on another end of said auxiliary member and engaging the top of said main member whereby said auxiliary member may be moved against the action of said spring means about said tongue-shaped end piece within said slot so as to cause said auxiliary member to assume a receding position in which said guide edge will be located substantially flush with said flat bottom surface of said main member to thereby obtain a substantially uninterrupted flat bottom surface, and means upwardly extending from said main portion for connection with the foot bar of a sewing machine.

3. A presser foot structure of the character described comprising a main foot portion provided with a substantially flat bottom surface terminating in a lateral edge, said main portion having a slot substantially parallel to said lateral edge, an auxiliary foot member accommodated for movement in said slot, said auxiliary member including a guide edge for the end of a work piece, opposite guide pieces arranged on said main portion, an extension member positioned on top of said main portion and slidable along said guide pieces, said extension member including a flange in normal position contiguous with said lateral edge and substantially flush with the bottom surface of said main portion, said flange being spaced from said lateral edge of said main portion in extended position of said extension member and aiding in the depression of a portion of the work piece when projecting beyond

said guide edge, spring means engaging said auxiliary member to maintain the latter in position within said slot, a tongue-shaped end piece forming part of said auxiliary member and retained on top of said main portion, whereby said auxiliary member may be moved against the action of said spring means to recede within said slot to a position in which said guide edge of said auxiliary member comes to lie substantially flush with said flat bottom surface of said main portion to further aid in the depression of said work piece portion, and means on said main portion for connection with the foot bar of a sewing machine.

4. A presser foot structure of the character described comprising a main foot portion provided with a substantially flat bottom surface terminating in a lateral edge, said main portion having a slot substantially parallel to said lateral edge, an auxiliary foot member accommodated for movement in said slot, said auxiliary member including a guide edge for contact with a part of a work piece, an extension member on top of said main portion and arranged for sliding movement thereon, said extension member including a flange normally positioned adjacent said lateral edge and substantially flush with the bottom surface of said main portion, said flange being spaced from said lateral edge of said main portion in extended position of said extension member for contact with another part of said work piece, spring means disposed on said main portion and resiliently supporting said auxiliary member to maintain the latter in position within said slot, a tongue-shaped end piece forming part of said auxiliary member and projecting to said top of said main portion, whereby said auxiliary member may be moved against the action of said spring means to recede within said slot to a position in which said guide edge of said auxiliary member comes to lie substantially flush with said flat bottom surface of said main portion for engagement with said work piece therebelow, and means extending from said main portion for connection with the foot bar of a sewing machine.

5. A presser foot structure of the character described comprising a main foot portion provided with a substantially flat bottom surface terminating in a lateral edge, said main portion having a slot substantially parallel to said lateral edge, an auxiliary foot member accommodated for movement in said slot, said auxiliary member including a guide edge for the engagement with a part of a work piece, an extension member on top of said main portion and arranged for sliding movement thereon, cooperative adjusting means provided, respectively, on said main portion and on said extension member to position the latter relatively to said main foot portion, said extension member including a flange substantially flush with the bottom surface of said main portion, said flange upon assuming extended position of said extension member being adapted for contact with another part of said work piece, spring means held by said main portion and resiliently supporting said auxiliary member to maintain the latter within said slot, and means extending from said main portion for connection with the foot bar of a sewing machine.

6. The combination of a presser foot device, with an auxiliary presser foot, and an extension member for said presser foot device, said auxiliary presser foot and said extension member being mounted for support on top of said presser foot device, said extension member being dis-

posed for movement transversely to said auxiliary presser foot, said presser foot being provided with a transverse slot for accommodating therein said auxiliary presser foot and for movement thereof in substantially perpendicular direction to said presser foot device, whereby said extension member and said auxiliary presser foot may be employed for retaining a work piece on the platform of a sewing machine during sewing operations.

7. The combination of a presser foot device, with an auxiliary presser foot, and an extension member for said presser foot device, said auxiliary presser foot and said extension member being mounted for support on top of said presser foot device, said extension member being disposed for movement transversely to said auxiliary presser foot, said presser foot being provided with a transverse slot for accommodating therein said auxiliary presser foot and for movement thereof in substantially perpendicular direction to said presser foot device, whereby said extension member and said auxiliary presser foot may be employed for retaining a work piece on the platform of a sewing machine during sewing operations, and spring means interposed between said presser foot device and said auxiliary presser foot and permitting receding of said auxiliary presser foot to alignment position and substantially flush with the bottom surface of said presser foot device.

8. In a presser foot device for use on sewing machines; an auxiliary presser foot, an extension member for enlarging said presser foot device, said auxiliary presser foot and said extension member being mounted for support on top of said presser foot device, means for adjusting said extension member on said presser foot device, said extension member being disposed for movement transversely to said auxiliary presser foot, said presser foot device being pro-

vided with a slot for accommodating therein said auxiliary presser foot and for movement of the latter in substantially perpendicular direction to said presser foot device, whereby said extension member and said auxiliary presser foot may be employed for retaining a work piece on the platform of a sewing machine during sewing operations.

9. A device of the character described comprising a main presser foot having a substantially flat bottom surface, an auxiliary presser foot, an extension member for said main presser foot, said auxiliary presser foot and said extension member engaging for support said main presser foot on the top thereof, said extension member being disposed for sliding movement transversely to said auxiliary presser foot, said main presser foot being provided with a slot for accommodating therein said auxiliary presser foot and for movement of the latter in substantially perpendicular direction to said main presser foot, whereby said main presser foot, said extension member and said auxiliary presser foot may be employed for retaining a work piece on the platform of a sewing machine during sewing operation, and spring means interposed between said main presser foot and said auxiliary presser foot and permitting receding of said auxiliary presser foot to alignment position and substantially flush with the bottom surface of said main presser foot.
